F. W. ROBERTSHAW

THERMOSTATIC VALVE

Filed Jan. 29, 1924

INVENTOR

Frederick W. Robertson,
James Brown Carmelite
his Cott.

UNITED STATES PATENT OFFICE.

FREDERICK W. ROBERTSHAW, OF PITTSBURGH, PENNSYLVANIA.

THERMOSTATIC VALVE.

Application filed January 29, 1924. Serial No. 689,308.

The present invention relates broadly to hot water heating systems and thermostatic valves therefor, and more particularly to valves of the character adapted for use with 5 boilers of the hot water storage type for controlling the supply of combustible fluid to a burner, although the utility of the invention in this respect is not limited.

At the present time there is a growing 10 tendency toward the use of hot water storage tanks having a circulating connection leading from a lower portion of the tank to a heater, and thence to an opening in one 15 side of the tank. The present invention is especially adapted to a circulating connection of this character.

By the present invention there is provided 20 an improved arrangement enabling the maintenance of uniform temperature conditions in the boiler at all times.

Another object of my invention is to provide 25 an improved form of valve adapted for use in this connection, the valve being provided preferably with normally sealed means whereby the temperature at which the 30 valve operates to completely cut off the flow of gas, or operates to establish gas flow, may be easily adjusted, the sealing of said means preventing the valve from accident or mo-

lestination.

In the accompanying drawings there is shown, for purposes of illustration only, a preferred embodiment of the present invention, it being understood that the drawings 35 do not define the limits of my invention, as changes may be made in the construction and operation therein disclosed without departing from the spirit of the invention or scope of my broader claims.

40 In the drawings—

Figure 1 is a side elevation of a portion of a hot water heating system and its connections, including my improved thermostatic valve;

45 Figure 2 is a detail view on an enlarged scale of a portion of the valve;

Figure 3 is a vertical longitudinal sectional view through the construction illustrated in Figure 2, certain of the parts being 50 broken away and certain of the parts shown in elevation; and

Figure 4 is a detail view on an enlarged scale of a portion of the valve.

In accordance with the present invention 55 there may be provided a hot water boiler 2 of the storage type having an inlet 3 for

cold water and an outlet 4 for hot water. Leading from a point adjacent the bottom of the tank there is a circulating connection 5 supplying water to be heated to a heater 6, which heater may be of any usual and well known construction. After passing through the heater the water is adapted to be conducted to the boiler. This circulation is established by means of a connection 7 and my improved valve construction.

Referring more particularly to Figures 2 and 3 of the drawings, this valve may comprise a valve body 8 having an inlet connection 9 and an outlet connection 10, the 70 communication between which is controlled by a valve disk 11 cooperating with a seat 12 within the valve body. The connection 9 may cooperate with a gas supply line 13 while the outlet connection 10 may communicate with a gas line 14 leading to the burner for the heater 6, as well understood. For controlling the minimum supply of gas to the burner to prevent extinguishment thereof, there may be provided a by-pass 15 controlled by an adjustable needle valve 16. In order to seal this needle valve, and to prevent tampering therewith, there may be provided a cap 17.

The valve body 8 has projecting from the rear thereof a tubular water connection 18 having an inlet 19 adapted to cooperate with the circulating connection 7 and an outlet 20 threaded to receive a nipple 7' which is threaded at its opposite end into the side of 90 the boiler. By reason of this construction it will be apparent that hot water leaving the heater 6 passes through the connection 18 before entering the boiler. Extending through the connection 18 and the nipple 7' 95 and projecting into the boiler is an expandible tube 21 within which is mounted a relatively non-expandible member 21'. These relatively expandible and non-expandible members constitute a thermostatic control 100 by means of which the valve disk 11 is operated as will be hereinafter more fully described. As the members are not only subjected to the hot water leaving the heater but to the temperature of the water within 105 the boiler, it will be apparent that the operation of the valve is more nearly stabilized and intermittent rapid opening and closing movements thereof are prevented.

The valve disk has projecting from opposite sides thereof tubular stems 22 and 23. The stem 23 may be guided within the outer

end of the expansible tube 21 where it is secured in the valve body, while the stem 22 may be guided by removable valve cap 24 threaded into the valve body. This cap has 5 a central opening adapted to guide the stem as described and surrounding the opening is a recess 25 within which is mounted a felt washer 26 and a metallic washer 27. Abutting at one end against this metallic washer 10 and at its opposite end against the valve disk 11 is a compression spring 28. It will be apparent that this spring not only serves to normally urge the valve in one direction, but also serves to compress the packing 15 washer 26, whereby the interior of the valve body is effectively sealed against the escape of gas around the stem 22.

For transmitting operating pressure from the thermostat to the valve disk 11 in opposition to the action of the spring 28 there is provided a packing pin 29 extending through the tubular guide stems on the valve. At one end the packing pin is in engagement with the relatively non-expansible member 20 21', while at its opposite end it is in engagement with an adjusting screw 30. This adjusting screw is threaded through the end of the tubular stem 22 and is held in adjusted position therein by a binder set screw 31. This binder set screw projects at its outer end into a slot 32 formed in the externally threaded projection 33 on the valve cap. With this construction, by loosening the binder set screw, the adjusting screw 30 35 may be threaded inwardly or outwardly as required. If threaded outwardly, it will be apparent that the packing pin is urged toward the relatively non-expansible member 21' whereby contraction of the relatively expansible casing 21 will open the valve at an earlier stage than would be the case if the packing pin were moved in the opposite direction. In this manner the temperatures at which the valve disk is opened or closed 40 45 may be accurately controlled. During such adjustment of the adjusting screw, rotation of the valve disk with the adjusting screw is prevented by reason of the projection of the outer end of the adjusting set screw 31 into the slot 32. This adjusting mechanism for the valve may be protected and the interior of the valve further sealed against the escape of gas by a cap 34. It will be understood that the caps 17 and 34 have their inner 50 55 ends machined to cooperate with machined surfaces on the valve body, whereby tight fits are insured.

If desired, the end of the stem 22 may be extended as indicated at 22'. This extension, 60 where provided, will preferably be a polygonal cross section whereby in the event of loss of the binder set screw the end of the stem may be easily held to permit adjustment of the screw 30 as will be clearly understood.

I have found that the provision of a relatively short path of circulation, such as is insured where the circulating connection communicates with the side of the storage tank enables a uniform temperature to be 70 maintained due to the more rapid movement of the water through the cycle. With a valve construction as set forth, such a connection with the side of the storage tank is facilitated and the use of at least one fitting 75 is obviated.

The advantages of the present invention arise from the provision of an improved valve adapted to be easily controlled to adjust the temperatures at which it is operated.

Further advantages arise from the construction of the valve body whereby in the use thereof the thermostat may be partially subjected to the temperature of the water 85 leaving the heater and partially subjected to the temperature of the water within the boiler.

I claim:

1. In a thermostatic valve, a valve body 90 having inlet and outlet openings, a valve controlling communication between said openings, a tubular stem projecting from opposite sides of said valve, means for guiding said stem, thermostatic means for operating the valve, and a packing pin slidably mounted in said tubular stem, said packing pin co-operating with said stem at one end and with said thermostatic means at its opposite end, substantially as described. 100

2. In a thermostatic valve, a valve body 95 having inlet and outlet openings, a valve controlling communication between said openings, a stem projecting from opposite sides of said valve, means for guiding each 105 end of said stem, thermostatic means for operating said valve, and means co-operating with the end of the stem remote from the thermostatic means for adjustably controlling the operation of the valve, said last mentioned stem end projecting beyond said body to enable the same to be engaged and held during adjustment, substantially as described. 110

3. In a thermostatic valve, a valve body 115 having inlet and outlet openings, a valve controlling communication between said openings, a tubular stem projecting from said valve, means for guiding said stem, thermostatic means for operating the valve, a packing pin slidably extending through 120 said stem and engaging said thermostatic means at one end, and adjustable means establishing operative engagement between the opposite end of said pin and said stem, substantially as described.

4. In a thermostatic valve, a valve body 125 having inlet and outlet openings, a valve controlling communication between said openings, a hollow stem projecting from said 130

- valve, means for guiding said stem, thermostatic means for operating the valve, a packing surrounding said stem, means normally urging the valve in one direction in opposition to the thermostatic means and forcing said packing into engagement with said stem, a closure for one end of said stem, and adjustable means for said valve adapted to be exposed by removal of said closure, one end 5 of said stem projecting into said closure to permit the same to be engaged and held when the closure is removed, substantially as described.
5. In a thermostatic valve, a valve body 15 having inlet and outlet openings, a valve controlling communication between said openings, a stem projecting from said valve, means for guiding said stem, a thermostatic means for operating the valve, adjustable means establishing engagement between said valve and said thermostatic means, and means preventing rotation of said valve during the adjustment thereof, said last mentioned means being effective for maintaining 20 the adjustable means in adjusted position, substantially as described.
6. In a thermostatic valve, a valve body 25 having inlet and outlet openings, a valve controlling communication between said openings, thermostatic means for operating said valve and means for subjecting different portions of said thermostatic means to water at different temperatures, substantially as described.
7. In a thermostatic valve, a valve body 30 having inlet and outlet openings, a valve controlling communication between said openings, said valve having an opening therethrough, a pin slidably projecting 35 through said opening, thermostatic means detachably engaging one end of said pin, adjustable means engaging the opposite end of the pin and forming an operative connection between said opposite end of 40 said pin and said valve, and means for preventing rotation of said valve during the adjustment thereof, substantially as described.
8. In a thermostatic valve, a valve body 45 having inlet and outlet openings, a valve controlling communication between said openings, said valve having an opening therethrough, a pin slidably projecting 50 through said opening, thermostatic means detachably engaging one end of said pin, 55 and adjustable means engaging the opposite end of said pin and forming an operative connection between the pin and said valve, substantially as described.
9. In a thermostatic valve, a valve body 60 having inlet and outlet openings, a valve controlling communication between said openings, said valve having an opening therethrough, a packing pin slidably projecting through said opening, thermostatic 65 means engaging one end of said pin, and means engaging said pin for moving the same axially through said valve, substantially as described.
10. In a thermostatic valve, a valve body 70 having inlet and outlet openings, a valve controlling communication between said openings, a tubular stem projecting from said valve, means for guiding said stem, thermostatic means for operating the valve, 75 a pin slidably mounted in said stem and engaging said thermostatic means at one end, and a screw adjustably engaging said stem and said pin for effecting adjustment of 80 said valve, substantially as described.
11. In a thermostatic valve, a valve body having inlet and outlet openings, a valve controlling communication between said openings, said valve having a hollow stem projecting from opposite sides thereof, a 85 pin slidably mounted in said stem, an adjusting screw engaging one end of said pin, said stem on one end thereof being shaped to permit holding the valve against rotation while the screw is adjusted, and a 90 closure adapted upon removal to expose said screw, substantially as described.
12. In a thermostatic valve, a valve body having inlet and outlet openings, a valve controlling communication between said 95 openings, said valve having a guiding stem of angular cross section at one end thereof, a cap adapted to provide access to said stem, a pin within said stem, and adjusting means cooperating with said pin and adapted to 100 be adjusted upon removal of said cap, substantially as described.

In testimony whereof I have hereunto set my hand.

FREDERICK W. ROBERTSHAW.
